QUENCHED SPARK GAP

Wilhelm Schönfeld, Berlin, Germany, assignor to Telefunken Gesellschaft für Drahtlose Telegraphie m. b. H., Berlin, Germany, a corporation of Germany

Application November 30, 1938, Serial No. 243,219
In Germany November 13, 1937

2 Claims. (Cl. 250—38)

An object of this invention is to provide a quenched spark gap possessing a high quenching effect with very low self-capacitance and very low self-inductance.

The present invention is related to a new and novel series quenched spark gap which offers substantial advantages over similar arrangements known in the prior art. Fundamentally speaking, it is known to use rotating spark gaps for the generation of high frequency currents. For the production of short waves, in order that the ensuing oscillations may be of low damping and cooling of the discharge gaps, the inter-electrode distances must be extremely small.

Most favorable are distances of, say, an order of a few hundredths of 1 mm. Rotating the electrodes in reference to one another in the revolving series spark gaps known in the art, it will be found very difficult to observe or maintain such small distances or gaps, and the consequence is that even slight alterations will cause serious variations in operation. Another fact is that the spark gaps known in the art, of the rotary type, inhere considerable self-capacitance which represents a substantial shunt where ultra-short waves are dealt with.

According to the invention a quenched spark gap is designed in such a way that a series or row of juxtaposed series spark gaps is periodically passed between two stationary end or terminating electrodes upon which the discharge potential is impressed.

An exemplified embodiment of a spark gap as here disclosed consists of a rotatable hollow cylinder upon the shell or circumference of which the series spark gaps are disposed in the form of several adjacent rows covering the circumference of the cylinder parallel to the axis of rotation of the hollow cylinder, in such a way that upon rotation of the cylinder the various series of spark gaps are positioned between the two fixed electrodes at the beginning and the end.

The invention shall now be explained more fully by reference to the appended drawings which show this exemplified embodiment. Fig. 1 is a longitudinal section of the object of the invention; Fig. 2 is a cross-section. W denotes a steel shaft or spindle journaled in the ball bearings L, said shaft W being rotated by a motor M. The said shaft W supports a hollow cylinder H made of insulation material upon the circumference of which, being separated from one another by a thin layer of asbestos, are secured the copper radiator or cooling elements K. Welded onto the latter are the electrodes E, the

latter preferably being made of tungsten or electrolytic iron. E₁ and E₂ represent the two electrodes mounted at the beginning and at the end which are welded on the radiator or chilling bodies K₁ and K₂, respectively. These fixed cooling elements may be adjusted in distance relative to the spark gap by screw-threads G₁ and G₂, and they are cooled by the aid of vanes F₁ and F₂ attached to the shaft. As can be seen from the cross-sectional view Fig. 2 of the revolving part of the assembly, 24 series spark gaps are arranged on the circumference of the hollow cylinder in the particular exemplified embodiment here shown, which, upon rotation, are sequentially placed in a position between the electrodes E₁ and E₂. The cooling of the spark gap is insured by blasting a current of air against the same from below.

Now, the operation of the spark gap is as follows:

By rotation of the central electrode, ever freshly cooled and deionized gaseous paths or gaps are shifted into the spark path. This path or gap is fixed by the stationary outer electrodes E₁ and E₂ and fixed and defined by the line connecting the first and the last electrodes. In the instance here mentioned comprising 24 spark gaps around the circumference of the revolving hollow cylinder, as will thus be seen, a cold deionized gaseous path will enter the spark gap twenty-four times for each revolution. Thus, if the hollow cylinder requires for a revolution, say, one second, this means that the gas path of a series of consecutively disposed electrodes stays just one-twenty-fourth of one second in the spark path. In other words, the copper radiator elements K have $\frac{23}{24}$ of a second time to give off such heat as may have been generated. In the ten-unit spark gap as represented in the exemplified embodiment, the resultant thermal load of the spark gap amounts to only 400 watts. This load, in the case of a stationary spark gap, would have to be divided between twenty electrodes, whence the heat dissipated and to be carried away per electrode would amount to twenty watts. But in the rotary spark gap according to the present embodiment, the 400 watts are divided among a twenty-four times greater number of electrodes, whence a load of less than two watts. Owing to such low heat load and to the movement of the electrodes, the tendency to form craters is avoided, combined with very effective cooling and deionization. Because of such low heat load, moreover, the radiator elements can be made comparatively small.

in size. And this means very low self-capacitance of the entire assembly with the result that the shunt residing in this capacity and which for ultra-short waves is conducive to marked losses, is greatly reduced. The self-capacitance of the spark gap shown in the exemplified embodiment amounts, for instance, to only around 2 centimeters.

The abbreviation of the current path due to 10 the compact and crowded arrangement of the electrodes, as contrasted with the conventional stationary spark gap, amounts to about eighty percent. As a result, the self-induction of the 15 spark gap which constitutes part of the inductance of the oscillatory circuit is diminished considerably. The condenser of the oscillatory circuit, for the generation of waves of the same length, may therefore be made larger, and this means an appreciable raise in power.

20 Owing to the efficient cooling of the spark gap, it is possible to use extremely high spark frequencies, say, up to 10^6 per second, without the 25 spark becoming inductive as a result of inadequate or imperfect de-ionization. Also, this fact raises the oscillatory power or performance of the arrangement considerably.

By mounting additional stationary electrodes at the beginning and at the end, further spark 30 paths may be obtained which may be used either for impulsing other oscillatory circuits or as 35 spare gaps. To insure equally good cooling conditions in this case, the number of electrodes distributed over the periphery and the speed of rotation must be increased correspondingly.

35 The invention is not restricted to the exemplified embodiment illustrated in the drawings,

but a great many modifications are conceivable which fall inside the scope and spirit of the invention.

What is claimed is:

1. A quenched spark gap comprising a rotatable shaft, a ventilation vane mounted on said shaft for cooling said spark gap, an insulating cylindrical member secured to said shaft, a plurality of metallic discs mounted on said insulating cylindrical member, a plurality of metallic electrode members secured to both surfaces of each disc and forming a row of juxtaposed series spark gaps, a pair of fixed terminal electrodes, said discs arranged in a row periodically between said fixed electrodes so that electrical discharge 15 applied to one of said fixed terminal electrodes passes through said series spark gaps and is discharged at an opposite fixed terminal electrode.

2. A quenched spark gap comprising a rotatable device, a rotatable shaft secured to said 20 rotatable device, a ventilation vane mounted on each end of said shaft for cooling said spark gap, an insulating cylindrical member secured to said shaft, a plurality of metallic discs mounted on said insulating cylindrical member, a plurality of metallic electrode members secured to both surfaces of each disc and forming a row of juxtaposed series spark gaps, a pair of fixed 25 terminal electrodes located adjacent said ventilation vanes, said discs arranged in a row periodically between said fixed electrodes so that electrical discharge applied to one of said fixed terminal electrodes passes through said series spark gaps and is discharged at an opposite 30 fixed terminal electrode.

35 WILHELM SCHÖNFELD.
